(57) **CLAIM**

The ornamental design for a pattern for sanitary article top, as shown and described.

DESCRIPTION

FIG. 1 is a plan view of a first embodiment of a pattern for sanitary article top showing my new design; and,

FIG. 2 is a plan view of another embodiment thereof. The broken line showing of portions of the pattern for sanitary article top in FIGS. 1 and 2 forms no part of the claimed design.

The grayscale fill in the figures includes some variations in color intensity. No particular color or color intensity is being claimed.
